CLAIM

The ornamental design for the amphibious sport aircraft, as shown and described.

DESCRIPTION

The present application relates to U.S. Design patent application Ser. No. 29/319,641 filed Jun. 11, 2008 entitled Amphibious Sport Aircraft with Wing-Fold, which is hereby incorporated by reference in its entirety for all purposes as if fully set forth herein.

FIG. 1 is a front perspective view of an amphibious sport aircraft showing our new design;

FIG. 2 is a front elevation view;

FIG. 3 is a rear elevation view;

FIG. 4 is a right side elevation view;

FIG. 5 is a left side elevation view;

FIG. 6 is a top plan view; and,

FIG. 7 is a bottom plan view.
